ENGINE STARTING APPARATUS

John B. Dyer, Pendleton, Ind., assignor, by mesne assignments, to General Motors Corporation, Detroit, Mich., a corporation of Delaware

Application August 16, 1933, Serial No. 685,315

4 Claims. (Cl. 290—38)

This invention relates to starting apparatus for internal combustion engines and more particularly to those of automotive vehicles.

Starting apparatus for internal combustion engines of the semi-automatic type, which includes a starting motor designed to be rendered operative upon the closing of the ignition switch and a second switch operable by some of the ordinary control devices of the vehicle such as the accelerator pedal or clutch pedal and rendered inoperative by engine suction when the engine is running under its own power is old, in which action of engine suction opens either the switch which is closed by the above mentioned vehicle control, or a separate switch in the starting motor circuit, and an example of such apparatus is disclosed in applicant's copending application Serial No. 594,553, filed February 23, 1932.

In devices of this character which have already been designed, it has been found difficult to provide a suction operated switch which is sufficiently sensitive to remain open under all operating conditions when the engine is running under its own power and which is not so sensitive as to be opened during the cranking of the engine by the starting motor. For instance, when the engine is under sufficiently heavy load with wide open throttle as when the vehicle is ascending a steep incline, the suction is very low and it has been difficult to design a suction-controlled switch which will remain in open position under such circumstances and which will not open during engine cranking.

It is the principal object of the present invention to provide a suction-operated switch which will remain closed at all times during the cranking of the engine by the starting motor, but which will be held open by the engine suction under all conditions of speed and load when the engine is operating under its own power. According to the present invention, this object is accomplished by the provision of a diaphragm subject to engine suction and operative to effect the movement of the movable switch contact, which diaphragm is constructed of thin sheet metal such as spring steel and which is so designed that a considerable degree of suction is required to move the diaphragm from its switch closed position to switch open position, but a very low degree of suction will be effective to hold the diaphragm in its switch open position after it has once been moved to such position.

Further objects and advantages of the present invention will be apparent from the following description, reference being had to the accompany-

ing drawing wherein a preferred embodiment of the present invention is clearly shown.

In the drawing:

Fig. 1 is a wiring diagram of one form of the present invention.

Fig. 2 is a detail, sectional view of a preferred form of the suction-controlled switch.

Fig. 3 is a fragmentary, detail view of a modified form of the suction-controlled switch.

Referring to Fig. 1, the starting motor 10 is grounded at 12. As illustrated, this starting motor is adapted to drive the engine through the medium of the well-known Bendix drive (not shown). The motor 10 is connected by wire 14 with one fixed contact 16 of a magnetic switch 15 indicated in its entirety by the letter A, while the other fixed contact 18 is connected by wire 20 with a wire 22 leading to a battery 24 grounded through the connection 26. Cooperating with the contacts 16 and 18 is a movable contact 28 carried by the armature 30 of a solenoid comprising a core 32 surrounded by winding 34, the movable contact being normally held in open position by a spring 36, while a housing 38 encloses the winding. When this magnetic switch is closed current will flow from the battery through wires 22, 20, switch A, wire 14 to the starting motor, through the ground connection 12 to ground and through ground connection 26 to the battery, thus causing the starting motor to operate.

The magnetic switch is adapted to be closed upon closing of the ignition switch and another switch indicated in its entirety by the letter B, which is adapted to be closed by the accelerator pedal which controls the quantity of fuel mixture supplied by the carburetor to the engine. The magnetic switch is caused to open when the engine is running under its own power and is prevented from closing as long as the engine continues to run under its own power by the action of engine suction which operates the switch B and thus causes the magnet of said magnetic switch to be de-energized so that the magnetic switch will remain open as long as the engine suction remains sufficient to hold the switch B open.

The winding of the magnetic switch A is grounded by a wire 40 and the other end of the winding is connected by wire 42 to one of the fixed contacts 44 of the switch B, while the other fixed contact 46 of said switch is connected by a wire 48 with a wire 50 which leads from the fixed contact 52 of the ignition switch to the ignition system of the engine. The movable contact 54 of the ignition switch is con-

nected by the wire 56 with the wire 22 which leads to the battery, as previously described. The wire 22 is also connected by a wire 60 with a generator 62 which is grounded at 64 and is 5 provided with the usual cut-out relay 66.

The circuit above described operates as follows. When the ignition switch 54 and the switch B, which is adapted to be closed by the accelerator pedal as hereinafter more specifically 10 set forth, are both closed, current will flow from the battery which is grounded through the connection 26 through the wires 22 and 56, the ignition switch, wire 48, switch B and wire 42 to the winding of the magnetic switch A and 15 through the connection 40 to ground. This will energize the magnetic switch A and cause the movable contact member 28 to be moved into engagement with the fixed contacts 16 and 18 at which time current will flow from the battery 20 through the wires 22 and 20, contacts 18, 28, and 16 and wire 14 to the starting motor and through the connection 12 to ground. When the 25 circuit of the starting motor is closed in this manner, the motor will become operative to start the engine and when the latter begins to run under its own power, the switch B will be opened by engine suction in a manner more fully described later. When this takes place, the circuit 30 through the winding of the magnetic switch A will be broken, the magnet of such switch will be de-energized and the contact 28 will be out of engagement with contacts 16 and 18 to break the starting motor circuit and thus cause the starting motor to become inoperative.

35 The switch B comprises, in addition to the fixed contacts 44 and 46, a movable contact 68 which is shown in Fig. 2 and is adapted to be rotated so as to be moved into engagement with the fixed contacts 44 and 46 by means of an 40 arm 70, which is adapted to be connected in any suitable way to the accelerator pedal which regulates the quantity of fuel mixture supplied to the engine. The switch B comprises a sheet metal housing 72 which is supported by a suitable 45 bracket mounted on the engine or in any desirable way. Riveted or otherwise secured to this housing is a diaphragm chamber formed of two cup-shaped sheet metal shells 74 and 76 suitably flanged and joined together so as to 50 form a fluid-tight joint with a diaphragm 78 secured between the flanges. As shown in the drawing, the metal shell 76 is provided with a flange which is pressed over the edge of the diaphragm and the cooperating flange on the 55 shell 74, as clearly shown in Fig. 2. The housing 72 is closed at one end by a circular block of insulating material 80 which supports the fixed contacts 44 and 46.

Secured to and supported at one end by the 60 diaphragm 78 and extending through an opening 82 in the housing 72 is a cylindrical element 84 which has a stud or spindle 86 projecting from its opposite end. Pivotaly mounted on the stud 86 is the movable contact member 68 65 previously referred to. This contact member has two arcuate contact surfaces 88 formed thereon, which are adapted to be moved into contact with the fixed contacts 44 and 46 when the contact member 68 is rotated in the manner more 70 specifically described later. The contact member 68 is held flat against the closed end of the cylindrical member 84 by washers 90 and a locking clip 92 which engages a groove (not shown) in the stud 86. Posts 94 are secured in the 75 housing 72 on opposite sides of the cylindrical

member 84 and act as stops to limit the movements of the contact member 68, while a helical spring 96 is connected at one end to one of said posts and at the other end to the contact member 68 so that the spring tends to hold the contact 5 member in its normal open position. The structure above described is all old and is more fully illustrated in applicant's copending application Serial No. 643,375, filed November 19, 1932.

In order to move the contact member 68 into 10 engagement with the fixed contacts, there is provided a sleeve 98 which is closed at one end, the closed end fitting within a suitable recess in the closure member 80, while projecting therefrom is a stud 100 to which the arm 70 previously mentioned is secured in any desirable manner. This sleeve is provided with slots 102 which embrace the movable contact member 68 when the device is assembled and shoulders 104 are provided on one side of each of these slots for a 20 purpose to be specified later. The closure member 80 may be held in place in any suitable manner, as for instance by tangs extending from the member 72 and bent over the edge of the member 80, in the manner described in the above 25 mentioned application Serial No. 643,375.

An internally threaded nut 106 is suitably secured to the shell 76 so as to form a fluid-tight joint therewith and a suitable suction connection 30 is adapted to be threaded into said nut and to extend to the intake manifold in order to communicate the manifold vacuum to the interior of the shell 76. Suitably mounted within the shell 76 and engaging the rounded head 108 of the member 84 which is secured to diaphragm 35 78, is a sheet metal disk 110 made of suitable material such as steel or bronze for example, which is adapted to be acted upon by the engine vacuum and normally holds the parts in the position shown in Fig. 2 with the contact member 68 in engagement with the inner face of the closure member 80. The disk 110 exerts a pressure on the head 108 which is sufficient to overcome the pressure of a spring 112 which normally tends to move the contact member 68 away from 40 the face of the closure member 80 and aids the engine suction in bringing about this result when such suction is communicated to the disk 110. It will be understood that the disk 110 is performed by a pressing operation before assembly 45 into a somewhat concavo-convex shape and when assembled, the slightly convex side of the disk is downward.

The action of this disk 110 is very similar to the action of the ordinary manually operable oil 50 can. It normally occupies the position shown in Fig. 2 and when the suction of the engine is communicated to the upper side of such disk, the disk will be moved upwardly from the position shown in Fig. 2. Normally the disk exerts a considerable degree of pressure tending to hold the parts in the position shown in Fig. 2, so much in fact that it requires a suction of substantially four inches of mercury to overcome the normal pressure of the disk and move it from the position 55 shown in Fig. 4, but as it approaches its dead center position, this pressure is progressively reduced. This operation of the disk is the familiar action of the oil can above referred to, and after the disk has assumed its upper position, although it will return to its lower position, if the suction falls sufficiently, it is found that a very small degree of suction, not more than a half inch of mercury, for example, is sufficient to hold the disk in its upper position. The spring 60 70 75 80 85 90 95 98 100 102 104 106 108 110 112 114 116 118 120 122 124 126 128 130 132 134 136 138 140 142 144 146 148 150 152 154 156 158 160 162 164 166 168 170 172 174 176 178 180 182 184 186 188 190 192 194 196 198 200 202 204 206 208 210 212 214 216 218 220 222 224 226 228 230 232 234 236 238 240 242 244 246 248 250 252 254 256 258 260 262 264 266 268 270 272 274 276 278 280 282 284 286 288 290 292 294 296 298 300 302 304 306 308 310 312 314 316 318 320 322 324 326 328 330 332 334 336 338 340 342 344 346 348 350 352 354 356 358 360 362 364 366 368 370 372 374 376 378 380 382 384 386 388 390 392 394 396 398 400 402 404 406 408 410 412 414 416 418 420 422 424 426 428 430 432 434 436 438 440 442 444 446 448 450 452 454 456 458 460 462 464 466 468 470 472 474 476 478 480 482 484 486 488 490 492 494 496 498 500 502 504 506 508 510 512 514 516 518 520 522 524 526 528 530 532 534 536 538 540 542 544 546 548 550 552 554 556 558 560 562 564 566 568 570 572 574 576 578 580 582 584 586 588 590 592 594 596 598 600 602 604 606 608 610 612 614 616 618 620 622 624 626 628 630 632 634 636 638 640 642 644 646 648 650 652 654 656 658 660 662 664 666 668 670 672 674 676 678 680 682 684 686 688 690 692 694 696 698 700 702 704 706 708 710 712 714 716 718 720 722 724 726 728 730 732 734 736 738 740 742 744 746 748 750 752 754 756 758 760 762 764 766 768 770 772 774 776 778 780 782 784 786 788 790 792 794 796 798 800 802 804 806 808 810 812 814 816 818 820 822 824 826 828 830 832 834 836 838 840 842 844 846 848 850 852 854 856 858 860 862 864 866 868 870 872 874 876 878 880 882 884 886 888 890 892 894 896 898 900 902 904 906 908 910 912 914 916 918 920 922 924 926 928 930 932 934 936 938 940 942 944 946 948 950 952 954 956 958 960 962 964 966 968 970 972 974 976 978 980 982 984 986 988 990 992 994 996 998 999 1000

112 is a relatively weak spring and is only strong enough to move the parts when the pressure of the disk 110 thereon is relieved.

In Fig. 3 is shown a modified form of the invention in which instead of employing a separate metal diaphragm in addition to that to which the movable switch contact is connected, such as the diaphragm 110 shown in Fig. 2, the said movable contact may be connected directly to a metal diaphragm preferably of steel and indicated by the reference character 120. In other respects the construction shown in Fig. 3 is the same as that previously described and the operation is the same. When the parts occupy their normal position, such as shown in Fig. 2, the pressure exerted by the diaphragm tending to hold the movable contact against the face of the member 80 is quite considerable, but as the vacuum increases and approaches a predetermined amount, the 20 downward bow of the disk 110 gives away and the disk moves with a snap movement and takes a position where the upper face of the disk becomes the bowed face, such movement causing opening of the switch contacts. It takes a lesser 25 degree of vacuum to hold the disk in this position than to move it to such position because of the tendency of the disk to assume its preformed shape. For example, a suction of about a half inch of mercury will hold the disk in position, 30 while a suction of substantially four inches of mercury is necessary to move the disk as described.

While the embodiment of the present invention as herein disclosed, constitutes a preferred form, it is to be understood that other forms might be adopted, all coming within the scope of the claims which follow.

What is claimed is as follows:

1. Control apparatus for an internal combustion engine comprising a starting motor, a current source, means for controlling the connection of the starting motor with the current source including a switch having stationary and movable contacts, suction operated means for causing the disengagement of the movable contact from the stationary contact while the engine is running under its own power, said suction operated means comprising a member adapted to hold said movable contact in switch closing position, and means 45 communicating the engine suction to said member, said member being deformed by effect of the suction thereon to operate said switch and so constructed that the force inherent in the member itself and exerted by said member in opposition to the suction is greater when the switch is in its closed position than its force opposing the effect of suction after said member has been moved to position to open the switch, whereby the suction of the engine during cranking and before starting to run under its own power is insufficient to effect opening of the switch, but the suction at any possible operating speed when the engine is operating under its own power is sufficient to hold the switch open.

65 2. Control apparatus for an internal combustion engine comprising a starting motor, a current source, means for controlling the connection of the starting motor with the current source including a switch having stationary and movable contacts, and suction operated means 70 for causing the disengagement of the movable contact from the stationary contact while the

engine is running under its own power, said suction operated means comprising a resilient metallic diaphragm movable to different positions and adapted to effect opening of the switch when moved to one of its positions, said diaphragm 5 being deformed by the effect of suction thereon, and so constructed that the force inherent in the member itself and exerted by said diaphragm in opposition to the suction is greater when the switch is in its closed position than its force opposing the suction after said diaphragm has been moved to position to open the switch, whereby the suction of the engine during cranking and before starting to run under its own power is insufficient to effect opening of the switch, but 15 the suction at any possible operating speed when the engine is operating under its own power is sufficient to hold the switch open.

3. Control apparatus for an internal combustion engine comprising a starting motor, a current source, means for controlling the connection of the starting motor with the current source including a switch having stationary and movable contacts, suction operated means for causing the disengagement of the movable contact from the stationary contact while the engine is running under its own power, said suction operated means comprising a spring steel diaphragm connected to the movable switch contact and adapted to move said contact to open the switch, said diaphragm being deformed by the action of suction thereon, and so constructed that the force inherent in the member itself and exerted by said diaphragm in opposition to the suction is greater when the switch is in its closed position than its force opposing the suction after said diaphragm has been moved to position to open the switch, whereby the suction of the engine during cranking and before starting to run under its own power is insufficient to effect opening of the switch, but the suction at any possible operating speed when the engine is operating under its own power is sufficient to hold the switch open.

4. Control apparatus for an internal combustion engine comprising a starting motor, a current source, means for controlling the connection of the starting motor with the current source including a switch having stationary and movable contacts, and suction operated means for causing the disengagement of the movable contact from the stationary contact while the engine is running under its own power, said suction operated means comprising a concavo-convex 55 spring steel diaphragm connected to and normally exerting a force tending to hold the switch closed, and adapted to be moved to open the switch, said diaphragm being deformed by the action of suction thereon, and so constructed that the force inherent in the member itself and exerted by said diaphragm in opposition to the suction is greater when the switch is in its closed position than its force opposing the suction after said diaphragm has been moved to position to open the switch, whereby the suction of the engine during cranking and before starting to run under its own power is insufficient to effect opening of the switch, but the suction at any possible operating speed when the engine is operating under its own power is sufficient to hold the 60 switch open.

JOHN B. DYER.
